(57) **CLAIM**

The ornamental design for a spacer for a sliding door rail, as shown and described.

DESCRIPTION

FIG. 1 is a perspective view of a spacer for a sliding door rail.

FIG. 2 is an alternative perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof.

FIG. 8 is a bottom plan view thereof; and,

FIG. 9 illustrates an example environment in which the spacer may be used (e.g., in conjunction with a sliding door rail).

The broken lines of FIG. 9 illustrate environmental matter and form no part of the claimed design.
